UNITED STATES PATENT OFFICE.

IANTHUS E. MARSHALL, OF RICHMOND, CALIFORNIA.

EXPANSIBLE HASP.

1,222,649.

Specification of Letters Patent. Patented Apr. 17, 1917.

Application filed May 17, 1915. Serial No. 28,643.

To all whom it may concern:

Be it known that I, IANTHUS E. MARSHALL, a citizen of the United States, residing at Richmond, in the county of Contra Costa 5 and State of California, have invented certain new and useful Improvements in Expansible Hasps, of which the following is a specification.

My invention relates to that class of hasps 10 which are freely expansible longitudinally, to be readily adapted to their staples; and has for its object the production of such a hasp which is simpler, and consequently more durable and cheaper to construct, than 15 any now known to the art.

My invention consists of a hasp member 20 composed of but two parts having a limited range of relative movement in a longitudinal direction. It is described more fully hereinafter in connection with the accompanying drawings, in which—

Figure 1 is a front elevation of my hasp.

Fig. 2 is a side elevation of the same.

Fig. 3 is an end section on the line $\alpha-\alpha$ 25 of Fig. 2.

Fig. 4 shows a modified form of my hasp, in which the anchor screws are covered by the body of the hasp when in the locked position.

Referring in more detail to the drawings, in all of which like numbers are used to represent the same element,—1 is an anchor plate adapted to be fastened in any suitable manner to one of two objects to be locked together, as for example, a door, or a chest-cover. This anchor plate 1 is of the usual type, and may be fastened to the door or other object in its extended position, as shown in Figs. 1 and 2 of the drawings, or 40 it may be folded under the body of the hasp, as in Fig. 4, in order that the screw-heads may be covered when the hasp is locked. Connected to the anchor plate 1 by the hinge 2 is the plate 3, which has at its outer end the integral wings 4. These wings 4 are bent into the form of hooks to act as guides for the plate 5. Plate 5 has at its inner end similar integral wings 6, so bent as to form guides for the plate 3. Plate 5 also has, at 45 its outer end, the slot 7 to fit over a staple or keeper 8 of the usual type.

Thus it will be seen that the plate 5 may be slid toward or away from the anchor plate 1, the hooked wings 4 and 6 forming 50 guides.

This sliding movement is limited in one direction by contact between the end of the plate 5 and the hinge 2, and in the other direction by contact between the guides 4 and 6. In this manner differences in the 60 relative positions of staple and anchor plate, as, for example, those caused by the shrinking or swelling of a wooden door, will not interfere with the proper engagement of the hasp. 65

Moreover, the integral construction of the guides 4 and 6 with the plates 3 and 5 respectively renders the manufacture of my hasp extremely simple, and reduces the number of operations necessary thereto to a minimum. 70

I am aware that minor variations may be made in the form and construction of this hasp without in any way affecting the essential principle involved, and I do not wish 75 to be understood as limiting myself in this regard.

I claim:—

An expansible hasp comprising an anchor plate; a primary plate having its inner end 80 pivotally connected with said anchor plate, and having at its outer end integrally formed wings projecting laterally from its side edges, said wings being bent upwardly and inwardly to form guides; a secondary 85 plate superposed upon said primary plate, said secondary plate having at its inner end integrally formed wings projecting from its side edges, said wings being bent downwardly and inwardly to embrace the edges 90 of said primary plate and to form guides therefor to permit relative lineal sliding movement between said plates, said movement being limited in one direction by the abutment of the inner end of said secondary 95 plate against the pivotal connection of said primary plate and said anchor plate, and in the other direction by the mutual abutment of the lugs upon the two plates; and means carried by the outer end of said secondary 100 plate for temporary attachment to a suitable keeper.

In testimony whereof I have signed my name to this specification in the presence of two subscribing witnesses.

IANTHUS E. MARSHALL.
